UNITED STATES PATENT OFFICE.

ROBERT M. SCHILLER, OF CHICAGO, ILLINOIS.

DESIGN FOR A PLATE.

Application filed July 10, 1924. Serial No. 10,112. Term of patent 14 years.

To all whom it may concern:

Be it known that I, ROBERT M. SCHILLER, a citizen of the United States, residing at Chicago, in the county of Cook and State of Illinois, have invented a new, original, and ornamental Design for a Plate, as shown in the accompanying drawing.

The drawing shows the new design as applied to a plate.

I claim:

The ornamental design for a plate substantially as shown.

ROBERT M. SCHILLER.
